UNITED STATES PATENT OFFICE

2,015,909

OIL BURNER

John J. Ritthamel, Chicago, Ill.

Application August 28, 1933, Serial No. 687,101

5 Claims. (Cl. 158—75)

The general object of my invention resides in the provision of a novel, simple and efficient oil burner and involves the mixture of steam, preferably superheated, with oil to produce an improved 5 combustion.

With this object in view my invention consists in certain features of novelty in the construction, combination, and arrangement of parts by which the said object and certain other objects, 10 hereinafter appearing, are effected, all as fully described with reference to the accompanying drawings and more particularly pointed out in the appended claims.

In the said drawings—

15 Figure 1 is a condensed top plan view of an oil burner embodying my invention;

Figure 2 is a partial condensed side elevation of the same with parts broken away and shown in section;

20 Figure 3 is a partial top plan section;

Figure 4 is a face view of one of the joint flanges of the structure;

Figure 5 is a partial section taken on the line 5—5 of Figure 2;

25 Figure 6 is a condensed sectional view of the water inlet structure of the device, hereinafter described;

Figure 7 is an end elevation of a portion of the structure shown in Figure 5; and

30 Figure 8 is a section taken on the line 8—8 of Figure 5.

Like characters of reference indicate like parts in the several views.

Referring to the drawings, 1 designates a hollow header provided with a steam inlet 2 and two oppositely disposed outlets 3, see Figures 1 and 3, and the header is provided with an interior partition structure 4 isolating the outlets 3 and provided with two valve ports 5 providing communication from the steam inlet 2 to the outlets 3 respectively.

Two valve devices 6 are suitably mounted in openings in the front of the header 1 and include longitudinally movable valve portions 7 cooperating with the ports 5 respectively for regulating the flow from the inlet 2 to the outlets 3 respectively, the valve device 6 being adjusted by means of hand wheels 8.

Two fuel charge forming and liberating devices 50 or burners are associated one with each of the outlets 3, and each of these burners comprises the following parts:

A hollow angle T fitting 9 has the middle portion thereof provided with a flange 11 which has 55 angular slots 12 therethrough and angularly

spaced thereabout. See Figures 1, 4 and 5. This middle portion of the fitting 9 is seated on the header 1 in coaxial continuing relation with an outlet 3 of the header, and is secured thereon by means of studs 13 secured on the header and 5 spaced about the outlet 3 and projecting through the slots 12 of the flange 11 and wedges 14 driven through holes in the studs and clamping the flange 11 between them and the header. By reason of the slots 12, the fitting 9 may be angularly adjusted on the header 1 for a purpose hereinafter described.

A relatively large tube 15 is secured into one of the other openings of the fitting 9 and projects therefrom, and a T angle fitting 16 is secured 15 at the third opening of the fitting 9 in coaxial relation with the tube 15. A relatively small tube 17 is secured in the main bore of the angle fitting 16 and extends therefrom within the tube 15 in coaxial spaced relation therewith. 20 See Figure 5.

The projecting or outlet end of the tube 17 is disposed inwardly of the corresponding projecting or outlet end of the tube 15 and is provided with an interior frusto-conical surface 18 25 forming a valve seat. A valve controlling device 19 is secured on the exterior end of the main bore of the fitting 16 and includes a valve stem 21 and a hand wheel 22 secured on the outer end of the stem.

30 A frusto-conical valve head 23 is disposed within the tube 15 adjacent the outlet end thereof and cooperates with the valve seat 18 of the tube 17, and is provided with a square shank 24 movably engaging within the tube 17. The 35 stem 21 of the valve controlling device 19 extends within the tube 17 and is secured to the shank 24 for regulating the flow from the tube 17 by the hand wheel 22.

The middle opening of the fitting 16 is connected 40 by a pipe line 25 with a source of oil under pressure, the pipe line being provided with a shut off valve 26.

A sleeve 27 is disposed within the tube 15 immediately inward of the outlet end of the tube 45 17 and is secured on the tube 17 by means of a set screw 28, see Figures 5 and 8, and this sleeve is provided with interior and external flutes 29 which form multiple jets of steam in the region of the outlet end of the tube 17 in the passage of 50 steam through the tube 15 toward its outlet end as will be further described.

The valve head 23 is provided with an outer enlarged portion 31 within the tube 15, which is fluted, as designated at 32, see Figures 5 and 55

7, and provides a second multiple jet forming means outwardly beyond the outlet end of the tube 17.

8 A steam generator is provided which comprises the following parts:

9 An upright pressure tight casing 33 is provided with a lower water inlet 34 and an upper steam outlet 35, and contained in the casing is a plurality of heat conductive elements 36, such as steel balls, providing interstices therebetween.

10 Water under pressure is fed into the casing 33 through the water inlet 34 by means of a pipe line 37 which is provided with a water regulating valve device including a valve seat 38, a valve head 39 on a stem 41 and a hand wheel 42 secured on the stem. See Figures 2 and 6. The pipe line 37 is also provided with a shut off valve 43.

11 Heat being applied to the casing 33, the water under pressure entering the same is converted into steam, the elements 36 within the casing accelerating the generation of steam in an obvious manner.

12 The steam outlet 35 of the steam generator is connected with the steam inlet 2 of the header 1 by means of a pipe 44, and a pressure safety valve 45 on the header serves to release excess steam pressure.

13 The steam generator is disposed so that the outlet ends of the tubes 15 and 17 are directed in the direction thereof, the hereinbefore described pivotal adjustment of the tubes providing for adjustably directing the combustion from the tubes particularly with reference to applying the proper amount of heat to the steam generator, it being contemplated that the steam generator be disposed in a fire box with the tubes directed thereinto.

14 The operation of the burner is as follows. Assuming the steam generator to be heated, say by combustion from an intimate mixture of oil and steam, liberated from the outlet ends of the tubes 15, superheated steam under pressure from the steam generator, passes under regulation by the valve devices 6 into the tubes 15 and, passing through the flutes 29, issues immediately in front of the outlet end of the tubes 17 in the form of multiple jets. Oil under pressure, pre-heated by reason of the steam in the tubes 15 surrounding the tubes 17 and the flow of which oil is regulated by the valve heads 23, issues from the outlet ends of the tubes 17 where it encounters the multiple jets of steam issuing from the flutes 29 of the sleeve 27 for intimate mixture therewith.

15 The mixture of steam and oil so formed then passes through the flutes 32 and issues from the outlet ends of the tubes 15 in the form of multiple jets where combustion takes place in the presence of air.

16 I do not wish to be limited to the precise details described as changes may be readily made without departing from the spirit of my invention, but having thus described my invention, I claim as new and desire to secure by Letters Patent the following:

17 1. In a device of the character described the combination of two tubes of different diameters disposed one within the other, in spaced relation and having corresponding outlet ends, the outlet end of the smaller tube being disposed inwardly of the outlet end of the larger tube, means for supplying steam under pressure to the larger of said tubes at a point remote from the outlet end thereof, means for supplying oil under pres-

sure to the smaller tube at a point remote from the outlet end thereof, multiple jet forming means within the larger tube in the region of the outlet end of the smaller tube and surrounding the smaller tube, and a second multiple jet forming means within the larger tube outwardly beyond the outlet end of the smaller tube. 5

18 2. In a device of the character described the combination of two tubes of different diameters disposed one within the other in spaced relation 10 and having corresponding outlet ends, the outlet end of the smaller tube being disposed inwardly of the outlet end of the larger tube, means for supplying steam under pressure to the larger of said tubes at a point remote from the outlet end 15 thereof, means for supplying oil under pressure to the smaller tube at a point remote from the outlet end thereof, multiple jet forming means within the larger tube in the region of the outlet end of the smaller tube and surrounding the 20 smaller tube, and a valve head operative upon the outlet end of said smaller tube for regulating the flow therefrom and provided with an enlarged portion arranged between the outlet ends 25 of said tubes and engaging the bore of the larger tube and formed with longitudinal flutes providing a second multiple jet forming means.

26 3. In a device of the character described the combination of two tubes of different diameters disposed one within the other in spaced relation 30 and having corresponding outlet ends, the outlet end of the smaller tube being disposed inwardly of the outlet end of the larger tube, means for supplying steam under pressure to the larger of said tubes at a point remote from the outlet end 35 thereof, means for supplying oil under pressure to the smaller tube at a point remote from the outlet end thereof, a longitudinally fluted sleeve engaged within the larger tube and engaged over the smaller tube at the outlet end thereof and 40 forming a multiple jet means, and a valve head operative upon the outlet end of the smaller tube for regulating the flow therefrom and provided with an enlarged portion arranged between the outlet ends of said tubes and engaging the bore 45 of the larger tube and formed with longitudinal flutes providing a second multiple jet means.

46 4. In a device of the character described the combination of a hollow header provided with a steam inlet and an outlet, two tubes of different 50 diameters, the smaller tube being disposed within the larger tube and the tubes having correspondingly disposed outlet ends, means mounted on said larger tube and said header whereby said tubes may be pivotally adjusted with respect to 55 said header at a point remote from the outlet ends thereof, said outlet of said header communicating with the larger tube through said means, means for supplying oil to the smaller tube at a point remote from the outlet end thereof, valve 60 means associated with said header for regulating the steam flow from said header to the larger tube, and additional valve means for regulating the flow of oil through the smaller tube. 60

65 5. In a device of the character described the combination of a hollow header provided with a steam inlet and two oppositely disposed outlets, two pairs of tubes, the tubes of each pair being of different diameters, the smaller tube of each pair being disposed within the larger tube there- 70 of and each pair of tubes having correspondingly disposed outlet ends, means mounted on said larger tubes and said header whereby said pairs of tubes may be pivotally adjusted independently 75

with respect to said header on axes transverse to said tubes at points remote from the outlet ends thereof, said outlets of said header communicating with the larger tubes respectively through said means, means for supplying oil to the smaller tubes at points remote from their outlet ends, valve means associated with said header for in-

dividually regulating the steam flow from said header to the larger tubes, and additional valve means operative at the outlet ends of the smaller tubes for individually regulating the flow of oil through the smaller tubes.
